UNITED STATES PATENT OFFICE.

ELMER C. OSBECK, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH.

Application filed November 23, 1925. Serial No. 70,733.

The present invention relates to latches for refrigerator doors and the like; and its object is, generally, to provide a device of that character improved in various respects 5 hereinafter appearing; and, more particularly, to provide a latch having means for minimizing the jars and strains sustained by the latch in suddenly closing the door on which it is mounted; and further, to provide in such a latch improved means for holding the latching bolt in partially retracted position and for releasing the same therefrom.

This and any other objects hereinafter appearing are attained by, and the invention finds preferable embodiment in, the structure hereinafter particularly described in the body of this specification and illustrated by the accompanying drawings, in which:—
20 Figure 1 is a front view of a latch and its keeper, shown partially in vertical section taken on line 1—1 of Figure 2;

Figure 2 is a vertical sectional view of the latch taken on line 2—2 of Figure 1;

25 Figure 3 is a front view of the latch and keeper, showing the latching bolt held in partially retracted position;

Figure 4 is a side view thereof; and

30 Figure 5 is a vertical sectional view of certain parts taken on line 5—5 of Figure 3.

In the accompanying drawings, a latch having a casing 1 is mounted on a door 2, the keeper 3 thereof being mounted on the door frame 4. The latch comprises a latching bolt 5 swingably mounted at 6 and spring-pressed at 20 into latching engagement with the recess 7 of the keeper when the door is closed. This bolt 5 is retracted from such engagement, to open the door, by drawing outwardly the lever handle 8 swing-

40 ably mounted at 9. This handle's horizontally disposed portion 10 engages said bolt to swing it upwardly and out of said latching engagement, passing through an opening 11 in the bolt. By drawing this handle outwardly from its normal and inoperative position shown in Figures 1 and 2, and to approximately the position seen in Figures 3, 4 and 5, the portion 10 of the lever han-

50 dle engages and moves the latching bolt upwardly far enough to cause it to be engaged holdingly by the handle, whose catch 12 has passed under and behind the bolt's lip 13 and thus holds the bolt partially retracted.

55 Assuming now the door to be open and the

latch's parts in the position seen in Figure 5: If the door be slammed shut, the outer end of the bolt, or the roller 14 with which it is desirably provided, strikes the inclined face 15 of the keeper, near its uppermost 60 point 16, as seen in Figure 4, whereupon the closing movement of the door continuing, the roller rides up and over said inclined face and its uppermost point and into the keeper's recess 7 behind said face. In so 65 doing the latching bolt is raised higher than its position seen in Figure 5, i. e., to a position in which the bolt is completely retract-
ed or raised high enough to permit the door 70 to open and close. It will be seen that thus the bolt is moved only a slight distance up-
wardly in slamming the door shut, i. e., the distance from partially retracted position 75 (seen in Figure 5) to completely retracted position, and thus the jars and strains sus-
tained by the latch and the screws 18 by
which it is secured to the door is minimized,
being much less than if the roller 14 trav-
elled the length of the keeper's face 15 in
closing the door. As the bolt rises from the 80 position seen in Figure 5 in the closing
movement of the door, it releases the catch
12 whereupon the handle lever 8 is returned,
as by its weight, to its normal inoperative
position seen in Figures 1 and 2. In open- 85
ing the closed door the lever handle is drawn
outwardly, thus raising the roller 14 high
enough to pass over the high point 16 of the
keeper and, such drawing movement con-
tinuing, the door is drawn open by the lever 90
handle. In thus opening the door, the lever
handle is lowered slightly to permit the
catch 12 to engage the bolt's lip 13 and
hold the bolt partially retracted in readiness
for the next closing of the door. 95

The invention being intended to be pointed out in the claims, is not to be limited to or by details of construction of the particular embodiment thereof illustrated by the drawings or hereinbefore described. 100

I claim:

1. In combination with a keeper therefor, a door latch comprising: a bolt adapted to latchingly engage the keeper; an operating handle movable to move the bolt to, and re- 105 leasably hold the same in, partially retracted position and movable farther to move the bolt to retracted position, the bolt and han-
dle having parts which mutually engage to hold the bolt in partially retracted position, 110

the bolt being also movable from partially retracted held position to retracted position by striking the keeper in the closing movement of the door.

- 5 2. In combination with a keeper therefor, a door latch comprising: a bolt adapted to latchingly engage the keeper; an operating handle movable to move the bolt to partially retracted position and having a catch en-
10 gaging the bolt to hold the same in said position, said handle being movable farther to move the bolt to retracted position and the bolt being also movable releasably from said catch by striking the keeper in the closing movement of the door.
- 15 3. In combination with a keeper therefor, a door latch comprising: a bolt adapted to latchingly engage the keeper; an operating handle movable from normally inoperative position to move the bolt to, and releasably hold the same in, partially retracted position and movable farther to move the bolt to retracted position, the bolt and handle having parts which mutually engage to hold
20 the bolt in partially retracted position, the
- 25

bolt being also movable from partially retracted position to retracted position and the holding engagement of the handle with the bolt being released to return the handle to normally inoperative position by the bolt 30 striking the keeper in the closing movement of the door.

4. In combination with a keeper having an inclined face, a door latch comprising: a bolt adapted to latchingly engage the keeper inside said face; an operating handle movable to move the bolt to, and releasably hold the same in, partially retracted position and movable farther to move the bolt to retracted position, the bolt and handle having parts which mutually engage to hold the bolt in partially retracted position, the bolt being also movable from partially retracted held position to retracted position by engaging said face of the keeper in the closing 40 movement of the door.

In testimony whereof I have hereunto set my hand at Grand Rapids, Michigan, this 19th day of November, 1925.

ELMER C. OSBECK.
